(57) **CLAIM**

The ornamental design for a single foodservice unit, as shown and described.

DESCRIPTION

FIG. 1 is a front perspective view of a single foodservice unit illustrating the invention design of flanking free-standing pylons on each side of the typical foodservice unit,

FIG. 2 is a rear perspective view of the foodservice unit of FIG. 1; and,

FIG. 3 is a front elevational view thereof.

The broken line showing of a typical foodservice counter and hanging signs is for illustrative purposes only and forms no part of the claimed design.
